FIG. 2.

UNITED STATES PATENT OFFICE

2,136,894

REFRIGERATOR FREIGHT CAR

Kent Schwebs, Hortonville, Wis.

REISSUED

JUL 1 - 1941

Application September 9, 1937, Serial No. 163,065

3 Claims. (Cl. 62—19)

This invention appertains to shipping of perishable articles, and more particularly to refrigerator freight cars and trucks, and is an improvement on my pending application, Serial No. 5 159,363, filed August 16, 1937.

In said application, I illustrated means for continuously circulating air through the foodstuffs and the ice bunkers to facilitate the cooling and keeping thereof, by the use of air-driven turbines.

10 Where compressed air was taken from the compressed air brakes for operating the turbines, there was the constant danger of taking too much air from the brake system, and the air compressors were expensive to maintain in working 15 condition.

It is, therefore, one of the primary objects of my invention to provide a pump mechanism operated in a novel manner from the car wheels for placing a liquid, such as oil, under pressure 20 and utilizing the liquid for operating a turbine, which, in turn, is utilized for actuating the fan for circulating the air through the car.

A further salient object of my invention is to provide a rockable platform on one of the car 25 trucks carrying a rotary pump and a drive shaft for the pump provided with a friction pulley urged into engagement with one of the car wheels for continuously operating the pump, with novel means for leading the fluid under pressure from 30 the pump to the turbine.

A further object of my invention is to provide a novel arrangement of pipes and valves for connecting the rotary pump with the turbine, whereby, irrespective of the direction of rotation of the 35 pump by the car wheels, the turbine will be continuously driven in one direction.

With these and other objects in view, the invention consists in the novel construction, arrangement, and formation of parts, as will be 40 hereinafter more specifically described, claimed, and illustrated in the accompanying drawing, in which drawing:

Figure 1 is a fragmentary longitudinal section through a refrigerated freight car, showing my 45 improved appliance incorporated therewith.

Figure 2 is a diagrammatic view illustrating the novel arrangement of pipes and valves for connecting the rotary pump with the turbine, whereby to rotate the turbine continuously in 50 one direction, irrespective of the direction of rotation of the pump.

Figure 3 is a detail fragmentary view illustrating the means utilized for operating the pump.

55 Referring to the drawing in detail, wherein

similar reference characters designate corresponding parts throughout the several views, the letter F generally indicates a refrigerator freight car, and the same embodies the usual insulated body 5 having formed at each end thereof bunkers 6 for the reception of ice 7. The ice rests on a grating 8 arranged above the level of the car floor. The body of the car is likewise provided with a suitable perforated false bottom 9, on which the foodstuffs to be shipped are placed. 10

In accordance with my invention, I arranged at the upper end of the bunker an air-circulating fan 10, which is adapted to draw air through the bunker and circulate the same over and through the foodstuffs in the car. It is to be 15 understood that a fan is provided at each end of the car, and the operation of the fan is such as to draw air from under the false floor 9, through the bunker, and over the top of the foodstuffs. The fan 10 is adapted to be driven by a 20 turbine 11, which can be of any desired make or character. If preferred, means can be provided for adjusting the position of the fan and turbine, and, if desired, the same can be mounted within a suitable hood 12. 25

In accordance with my invention, I provide novel means for supplying fluid under pressure to the turbine, and this means consists of a rotary pump 13. This rotary pump 13 is mounted upon a platform or lever 14. The lever 14 30 is rockably mounted at one end, as at 15, on a suitable portion of one of the trucks 16 of the freight car. The drive shaft 17 of the pump has keyed or otherwise secured thereto a friction pulley 18, which is adapted to rest upon the 35 periphery of one of the car wheels 19 of the car truck 16.

Spring means 20 may be provided for normally urging the lever 14 downwardly so that the friction pulley 18 will be held continuously in 40 engagement with its car wheel. The lever or platform 14 can also have mounted thereon a reservoir tank 21 for the liquid which is to be placed under pressure. I prefer to utilize oil, as oil will not freeze during the winter season 45 and will serve as means for maintaining the pump in good working condition at all times.

By referring to Figure 2, it can be seen that I connect with the ports 22 and 23 of the pump 13, liquid-conducting pipes 24 and 25 respectively. 50 These pipes 24 and 25 are in turn connected by T-couplings with pipes 26 and 27. The pipes 26 and 27, at one side, are connected with a pipe 28, which leads to the reservoir tank 21. The pipes 26 and 27 are connected on the other side with 55

a pipe 29, the purpose of which will be later described.

The pipe 26, on opposite sides of the pipe 24, has interposed therein one-way check valves 30 and 31. The pipe 27, on opposite sides of the pipe 25, has interposed in the length thereof one-way check valves 32 and 33. The pipe 28 has a pressure relief valve 34 interposed in the length thereof and this relief valve is connected with a 10 by-pass pipe 35 which leads to the reservoir 21.

All of these pipe and valves mentioned are preferably mounted upon the rocking platform or lever 14, and feed and return pipes 36 and 37 are arranged in the freight car. The feed pipe 36 is 15 connected with the pipe 28 by flexible pipe or hose 38, and the return pipe 37 is connected with the reservoir 21 by flexible pipe or hose 39.

The pipe 36 supplies fluid under pressure to one or more nozzles 40 for supplying the liquid 20 under pressure to the buckets of the turbine wheel. As the oil leaves the turbine wheel, the same is collected in the turbine casing and flows back into the reservoir through the pipes 37 and 38.

25 The arrangement of the pipes and valves on the car truck is such that, irrespective of the direction of the rotation of the pump by the car wheels, the turbine will be driven continuously in one direction.

30 By referring to Figure 2 and presuming that the pump is driven in a direction for forcing liquid under pressure through the pipe 24 and for drawing the liquid from the pipe 25, the liquid under pressure flowing through the pipe 24 will 35 seat the one-way check valve 30 and will open the one-way check valve 31, and this liquid under pressure will flow through the pipe 29 to the feed pipe 36 of the turbine. The pressure of the fluid will close the valve 33. The suction in the pipe 25 will open the one-way check valve 32, and consequently liquid will be drawn from the 40 reservoir.

If the pump is driven in a reverse direction, and the fluid is forced under pressure through the pipe 25, and liquid is drawn into the pump from the pipe 24, then the one-way check valve 33 will be opened, and the liquid will be supplied to the turbine through the pipe 29 and pipe 36. The liquid under pressure will seat the one-way check valve 32, and suction in the pipe 24 will open the 45 one-way check valve 30, and thus liquid will be drawn from the reservoir 21 to the pump. A line pipe 41 can be connected with the pipe 36 for conducting liquid under pressure to the turbine disposed at the opposite end of the car.

50 It is to be understood that various arrangements of the lever or platform 14 can be had, and that the same can be mounted in various manners on the car truck, and that the arrangement shown is only by the way of illustration. If desired, the 55 tank itself can form the lever or part thereof, and the tank can carry the pump and the check and safety valves.

55 While I have referred to the bunker 6 as receiving ice, it is to be understood that in the winter season a heater may be substituted for the ice, whereby the foodstuffs will be maintained against freezing.

During loading and while the car is standing still, extraneous motors can be utilized for operating the pump, or other means can be provided for circulating air through the car.

It is also to be understood that while I have 5 shown the pump driven from the car wheel, the pump can be driven in any preferred manner from any moving part of the car. Likewise, a centrifugal or other positive air displacement pump can be utilized.

Changes in details may be made without departing from the spirit or the scope of my invention, but what I claim as new is:

1. In a refrigerator car having a storage compartment therein and a bunker, of an air-circulating fan arranged adjacent to the bunker for drawing air therethrough and delivering air to the storage compartment, and means for operating the fan including a turbine, a pump for delivering liquid under pressure to the turbine, 20 means for driving the pump from a moving part of the car, and means for leading the liquid from the pump continuously in one direction to the turbine, irrespective of the direction of rotation of the pump.

2. A refrigerator car having a storage compartment therein and a bunker, of an air-circulating fan arranged adjacent to the bunker for drawing air therethrough and delivering air into the storage compartment, and means for operating the fan, including a turbine, a rotary pump, means for driving the pump from a moving part of the car, a reservoir, a feed pipe for liquid under pressure leading to the turbine, a return line for spent liquid, connecting the turbine with the reservoir, oppositely directed pipes connected with the ports of the pump, and a system of pipes and one-way check valves for connecting the last mentioned pipes with the feed and return pipes for continuously delivering liquid under pressure to the feed pipe, irrespective of the direction of rotation of the pump.

3. In a refrigerator car having a storage compartment and a bunker therein, of an air-circulating fan arranged adjacent to the bunker for drawing air therethrough and for delivering the air into the storage compartment, and means for operating the fan including a turbine, a rotary pump, a reservoir for liquid, a lever rockably mounted at one end upon one of the trucks of the car carrying the pump and the reservoir, a friction pulley connected with the drive shaft of the pump, spring means engaging the lever normally holding the friction pulley in engagement with one of the car wheels of the car truck, a feed pipe for conducting liquid under pressure of the turbine, a return pipe for conducting spent liquid from the turbine to the reservoir, oppositely directed pipes connected with the ports of the pump, branch pipes connected with the last mentioned pipes having one-way check valves at their terminals, means connecting the check valves at one side of the reservoir, and means connecting the check valves at the other side to the feed pipe.

KENT SCHWEBS.
